(57) **CLAIM**

The ornamental design for a jet nozzle, as shown and described.

DESCRIPTION

FIG. 1 is an isometric view of a jet nozzle showing the new design, wherein the broken line depiction of a removable face plate is included merely for illustrative purpose and forms no part of the claimed design.

FIG. 2 is a top plan view of the jet nozzle.

FIG. 3 is a bottom plan view of the jet nozzle.

FIG. 4 is a back view of the jet nozzle.

FIG. 5 is a first side view of the jet nozzle, the second side view being a mirror image thereof; and,

FIG. 6 is a front view of the jet nozzle.
